ELECTRIC PLUG

Albert E. Grant, New York, N. Y.

Application October 19, 1936, Serial No. 106,299

3 Claims. (Cl. 173—332)

My invention relates to wiring devices and more particularly to devices commonly known as heater plugs which are employed to connect current supply wires in circuit with electric heating appliances such as sad irons, waffle irons, bread toasters, etc., and this application is a continuation in part of my pending application Ser. No. 42,762 filed September 30, 1935.

Heretofore plugs of this character have usually embodied a casing formed of a plurality of co-mating parts secured together by means of screws, bolts, or other metallic fastening devices. A principal object of my invention is to provide an improved heater plug in which the molded insulating casing is in one piece.

A further object consists in providing an improved plug of this character in which the several parts are compactly and conveniently arranged in combination to facilitate assembly and to obtain a sturdy and well insulated device for the purpose. Other and further objects will appear from the following specification.

Referring to the drawing which forms a part hereof,

25 Figure 1 is a side elevation of a switchless heater plug embodying my invention.

Figure 2 is a vertical sectional view taken on line 2—2 of Figure 1.

30 Figure 3 is a vertical sectional view taken on line 3—3 of Figure 2.

Figure 4 is a cross sectional view taken on line 4—4 of Figure 3 and showing an inverted plan of my resilient rubber wire guard.

35 Figure 5 is an elevation of the interior sub-assembly carried in the casing of the device shown in Figures 1—4.

Figure 6 is a cross sectional view taken on line 6—6 of Figure 5 to show the improved binding terminal embodied in the modified device.

40 The insulating casing 70 consists of a deep molded shell of plastic composition having edge flanges 16 and side flanges 17' adjacent its top. The edge flanges are formed to provide a manual grip useful in withdrawing the plug to disconnect it and the side flanges define shoulders on opposite sides of the casing for engagement by the spring metal closure cap 60'.

45 The lower end wall of the casing is apertured at 21—21 to receive the contact prongs of an appliance with which it may be desired to make connection and the interior walls of the casing are molded to provide suitable shoulders and abutments for positioning and retaining the internal parts of the device. Thus formed, the housing is

readily molded in one piece and is of a conveniently handy size and shape.

The interior parts of the device constitute a sub-assembly, the combined elements of which are adapted to be dropped into the casing in 5 close nested relation. The sub-assembly, as shown in Figure 5, comprises a block of insulating material 75 carrying contact clips 27'—28' secured to the block by similar eyelets 29' and are spaced to register with the openings 21'.

10 One of the jaw members of each contact clip extends above its respective eyelet 29' and the extended portion is transversely bent and bifurcated by a gradually tapering slot to form a binding terminal 31', the wires 32' being doubled or 15 knotted and pinched into the slot. As best shown in Figure 6, outer side edges of the binding terminals 31' are notched opposite the inner end of the slot to weaken the metal so that when a wire 32' is pressed into the tapering slot, the bifurcated portions may yield slightly and, being resilient, grip the wire more firmly.

20 In this embodiment of my invention the wire guard 80 consists of a body of resilient material, such as a tough resilient rubber composition, 25 formed to provide a tubular sheath extending through the cap and adapted to surround and protect the insulating wires 32'. The lower end of the guard is flanged to form an integral resilient cushion 81 which is compressed between the underside of the cap and the block and serves by virtue of its resilience to hold the cap bead and flange securely against the casing shoulders and to hold the sub-assembly closely nested in the 30 casing.

25 As best shown in Figure 4, the lower surface of the cushion is recessed on opposite sides to accommodate the wires and the recessed areas 82 are corrugated, the corrugations extending transversely to the wires whereby the wires are more 35 securely gripped against the top of the block 75, any strain on the outwardly extending portions of the wires being absorbed so that it is not transmitted to the connections at the terminals 31'.

35 To assemble the device, the closure cap and 40 wire guard are first threaded over the wires and the wires are then connected to the binding terminals 31'. The sub-assembly is then dropped into the casing and the closure cap is brought 45 into engagement with the casing shoulders, thereby compressing the resilient cushion 81 against the top of the block, in which condition the cushion will tend to lift the cap and hold the cap bead and flange securely against the casing shoulders. To take down the assembly it is only 50 55

necessary to pry the bead of the cap from under the casing shoulder, whereupon the cap and the block 75 may be freely removed.

Having thus described my invention, I claim:

5. 1. A heater plug comprising a deep molded casing of insulating material having exterior shoulders formed on its opposite sides adjacent its top, a closure cap of resilient metal adapted to fit over the top of the casing and having inwardly extending edge portions adapted to engage said shoulders, conducting means carried within the casing, contacts carried by the casing and connected with said conducting means, said cap being perforate to admit current supply wires for connection to said means, and resilient means exerting an upward pressure on said cap to hold the edge portions thereof in engagement with said shoulders, said resilient means comprising an integral inner portion of a resilient rubber guard for said current supply wires extending through the cap perforation.
10. 2. A heater plug comprising a one-piece casing of insulating material, a sub-assembly nested in

the casing, a removable closure cap for the casing, and an insulating cushion of resilient rubber compressed between the sub-assembly and the cap to hold the sub-assembly firmly nested in the casing, said cushion having a tubular portion 5 integral therewith and extending through the cap for a considerable distance exteriorly thereof to provide a flexible guard for current supply wires.

3. A heater plug comprising a one-piece casing of insulating material, a sub-assembly nested in 10 the casing, said sub-assembly comprising a block of insulating material and contacts carried thereby and conducting means carried by the block and respectively connected to said contacts, a removable closure cap for the casing, and an insulating cushion of resilient rubber compressed between the sub-assembly and the cap to hold the sub-assembly firmly nested in the casing, said cushion having a tubular portion integral therewith and extending through the cap for a considerable distance exteriorly thereof to provide a 15 flexible guard for current supply wires.

ALBERT E. GRANT.
